UNITED STATES PATENT OFFICE

2,091,832

SLIDE FASTENER

Daniel I. Reiter, New York, N. Y., assignor to
 Glida Corporation of America, New York, N. Y.,
 a corporation of New York

Application April 1, 1936, Serial No. 71,994

3 Claims. (Cl. 24—207)

This invention relates to slide fastening devices and more particularly to such type of fastening device as set forth in U. S. Letters Patent No. 2,013,706, granted to Louis Wiesenfeld and Nathan Kase under date of September 10, 1935.

In slide fastening devices of the kind set forth in the above mentioned prior patent, the same includes a plurality of slide fastener members fixedly connected at spaced distances along a flexible element, the fastening members in turn being slidably associated with the bead edges of an opening to be closed to draw the edges together when the fastening device is in closed position, and for releasing the bead edges to facilitate spreading of the walls of the opening when the fastening device is in open position. The main object of this invention is to reduce the friction between the slide fastener members and the edges of the article on which they are captively and slidably associated which will provide a freer sliding movement of the fastener members to prevent accidental jamming of the same during sliding movement, and to reduce wear of the material from which the article is constructed.

Another feature of the invention resides in a slide fastener device having the above mentioned feature which does not increase the cost of manufacture over that of the slide fastener device set forth in the above mentioned patent.

Other objects of the invention will appear as the following specification is read in conjunction with the accompanying drawing, in which,

Figure 1 is a perspective view of a bag equipped with my improved slide fastener device.

Figure 2 is an enlarged vertical transverse sectional view on the line 2—2 of Figure 1.

Figure 3 is a detail perspective view of one of the slide fastener members per se.

Figure 4 is a rear elevational view of one of the slide fastener members.

Figure 5 is an enlarged vertical sectional view on the line 5—5 of Figure 4.

Figure 6 is a rear elevational view of a modified form of slide fastener member.

Figure 7 is a vertical transverse sectional view on the line 7—7 of Figure 6.

Figure 8 is a vertical sectional view of a further modification of slide fastener member.

Figure 9 is a rear elevational view of a still further modified form of slide fastener member.

Figure 10 is a vertical transverse sectional view on the line 10—10 of Figure 9.

Referring to the drawing by reference characters, the numeral 10 designates my improved

slide fastener device in its entirety and which is shown in Figures 1 and 2 of the drawing as being operatively associated with a bag 11. The bag 11 may be constructed of any flexible material, one side of which is open as at 12, the edges of 5 the walls of the bag at the opening 12 being formed with offset beads 13—13. The beads 13 are offset so that when the walls of the bag are brought together in closed relation, one bead laps the other as clearly shown in Figure 2 of 10 the drawing.

The slide fastener device 10 includes a plurality of substantially U-shaped slide fastener members 14 which are fixedly connected at spaced distances to a flexible element in the form of a 15 chain 15.

Each of the slide fastener members 14 is constructed of a single piece of flat stiff bendable metal, the same being bent into substantially U-shape to provide a rounded bight portion 16 20 and straight leg portions 17 and 18. The terminal end of the leg portion 18 is bent inwardly as at 19 and thence outwardly in rounded form to provide an eye 20. By reference to Figure 2 it will be seen that the eye 20 is inwardly offset 25 with respect to the leg 18 for a purpose to be presently explained.

The leg 17 has its terminal end provided with an inwardly punched teat or protuberance 21, the same being disposed opposite the rounded 30 inwardly bent portion 19 on the leg 18. In Figures 1 to 5 of the drawing, the teat 21 is rounded and has its inner surface convex so as to provide a minimum bearing contact with one of the side walls of the bag 11. The slide fastener members 14 are secured to the flexible element 15, by passing the element through the eyes 20. The eyes 20 are normally open as shown in Figure 5 but during assembly, the same are pressed closed about the flexible element to 40 clampingly engage the same.

Prior to the application of the slide fastener device 10 to the bag 11, the U-shape slide fastener members 14 are relatively open, but during attachment of the fastener device to the beaded 45 edges of the bag, the fastener members 14 are inserted over the beaded edges and pressure applied to the legs 17 and 18 to bend them about the edges to the form shown in Figure 2, at which time the beads 13—13 lie within the legs and bight portions whereas the terminal ends of the legs extend inwardly beyond the plane of the beads so that the inwardly bent portion 19 and the teat 21 slidably contact the exterior side walls of the bag. The inner rounded portion of 50 55

the eye 20 and the rounded teat 21 provide a minimum contact surface with the side walls of the bag and form a restricted entrance to prevent accidental pulling off of the members 14 from 5 the beaded edges.

To prevent accidental separation of the slide fastener member 10 from the bag, it is customary to captively secure one of the end fastener members 14 to the bag and this anchored member is 10 designated by the letter A. Thus an operator by grasping the other end slide fastener member may move the same toward the right in Figure 1 and slide all of the fastener members to a position at the right side of the bag, the anchor 15 member A serving as a stop. To close the fastening device, the free end slide member 14 is pulled toward the left to the position shown in Figure 1. By providing the minimum contacting surfaces between the terminal ends of the legs of the 20 U-shaped fastener members, the friction between the members and the walls of the bag is greatly reduced, thus permitting a freer sliding movement of the slide fastener members and a reduction of wear between the said members and the 25 walls of the bag.

Whereas I have illustrated the fastening device in association with a bag, it will be understood that the fastening device is adaptable for use on many other articles.

30 In Figures 6 to 10 inclusive, I have illustrated modified forms of protuberances which may be formed on the leg 17, all of which are punched inwardly from the leg and disposed inwardly of the confines of the edges of said leg. For instance, in Figures 6 and 7 the protuberance is elongated and designated 22, the same extending in a direction transversely on the leg on which it is formed. The protuberance 22 is well rounded on its inner side but in Figure 8 there is shown 40 a protuberance 23 which has its inner side pointed with the pointed end rounded. In Figures 9

and 10 of the drawing, the protuberance 24 is cone shaped with the tip of the cone rounded to avoid a sharp edge.

While I have shown and described what I consider to be the most practical embodiments of my invention, I wish it to be understood that such changes and alterations as come within the appended claims may be resorted to if desired.

Having thus described the invention, what I claim as new and desire to secure by Letters 10 Patent of the United States, is:—

1. A slide fastener comprising a U-shaped slide member having relatively thin flat terminal leg portions, one of said leg portions terminating in an inwardly offset round eye, a teat extending inwardly from the other leg portion of said U-shaped slide member opposite the said eye and having a rounded crown portion adapted to coact with said eye during sliding engagement of the slide fastener with opposite sides of an article 20 when in use.

2. A slide fastener comprising a U-shaped slide member formed from a single piece of stiff flat bendable material, an inwardly extending eye formed on the terminal end of one of the legs of said U-shaped slide member, and an inwardly extending teat formed on the other leg of said U-shaped slide member inwardly of the confines of the edges thereof and disposed opposite said eye, said teat having a rounded crown portion. 30

3. A slide fastener comprising a single piece of stiff flat bendable material bent into U-shape to provide a bight portion and leg portions, a round eye formed on the terminal end of one of the leg portions and projecting inwardly of the plane of the inner face thereof, and a rounded protuberance struck inwardly from the other leg portion and disposed opposite said eye for coaction therewith when the slide fastener is in use upon an article to be closed thereby. 40
